UNITED STATES PATENT OFFICE.

ALFRED O. RIDGWAY AND ALLAN FRALICK, OF LOS ANGELES, CALIFORNIA.

COMBINED CONTAINER AND TOY STAGE.

Application filed May 10, 1926. Serial No. 107,859.

This invention relates to a paper container for dry food products, so arranged that one of its walls may be cut away in order to utilize the container when emptied as a miniature toy stage.

An object of the invention is to provide a container for dry food products so arranged with pictorial representations on its interior walls that when the products are removed 10 and a wall is cut along indicated lines the empty container will form a miniature theatrical stage adapted for amusement purposes.

Briefly, the invention here shown consists in employing a paper box designed to hold 15 dry food products such as cereals, the interior surface of one of the side walls being provided with a pictorial representation of a scene from a play or motion picture, its oppositely disposed side wall being cut away 20 along certain indicated lines to form the representation of a stage proscenium and the remaining portion of said wall containing pictorial representations of the actors designed to be cut out for placement upon the 25 floor of the miniature stage formed from the food container.

In an embodiment of the invention as illustrated in the accompanying drawing:

Fig. 1 is a perspective view of a paper 30 container in a sealed form.

Fig. 2 is a similar view showing the container formed into a miniature toy stage.

Fig. 3 is a partial cross sectional view of the container showing a cut-away wall and 35 the pictorial representation of the actors designed to be cut therefrom.

Fig. 4 is a partial front elevation of the container after the same has been formed into a toy stage.

Referring now more specifically to the accompanying drawing 5 designates a rectangular pasteboard container consisting of a plurality of walls 7, 8, 9, 10, 11, and 12, secured together in the usual manner. Wall 45 11 on its exterior surface adjacent three of its edges is provided with dotted guide lines 13 to indicate the manner in which the cuts are made to form the miniature stage out of the container when emptied. When the 50 wall has been cut along the guide lines 13, the long narrow strips 14, 15, 16, are turned at substantially right angles to the walls 7, 8, and 9 to form the proscenium of the toy

stage, the vertical strips 14 and 16 being suitably engraved to form stage curtains 55 drawn apart, while the horizontally disposed strip 15 is also engraved to represent hanging curtains. The larger portion 17 of wall 11 has printed or engraved upon its interior surface a number of figures 18 representing the actors in the play, said figures adapted to be cut out and the bases 19 bent along the dotted indicating line 20, to form supports for the figures when mounted on the stage floor 10.

On the interior surface of wall 12 of the container is printed the pictorial representation of a scene from a motion picture play, or stage production, while the interior surface of the wall 10 which is intended to 70 represent the floor of the stage may be tinted or printed in a color similar to the ground shown in the scene.

Further, the illustration on the wall may represent an actual scene from a motion picture production not yet released, and the figures depicted on the wall 11 may be actual photographic reproductions of the players in the represented production in costume.

Also in order to increase interest the bases 80 19 of the figures may be suitably inscribed with the name of the player as well as the production on the paneled space directly above the players, a short synopsis of the production as represented by the pictorial 85 scene and players may be printed.

The containers, as heretofore noted, are especially adapted for holding dry food products, such as corn flakes, cakes, candies, dried fruits, in fact any commodity that 90 will not injure the interior surface of the container.

From the above description it will be apparent that we have provided a toy that will furnish considerable amusement to 95 small children at practically no cost. Further, by depicting scenes from popular motion picture plays, its value as an advertising medium will be obvious, not only on behalf of the play advertised but the manufacturers of the commodity contained in the box.

What we claim is:

In a toy stage, a rectangular container for commodities formed from a flexible material, 105 having on one of its interior walls a photo-

graphic or engraved reproduction from the scene of a theatrical play, its oppositely disposed wall adapted to be cut away along indicated lines on its outer surface to disclose the scene and form a miniature stage, said last named wall being provided with printed figures adapted to be cut therefrom for

mounting upon the wall forming the stage floor.

In witness that we claim the foregoing we ¹⁰ have hereunto subscribed our names this 8th day of April, 1926.

ALFRED O. RIDGWAY.
ALLAN FRALICK.
